UNITED STATES PATENT OFFICE

ERNST HEYMAN, OF FRANKFORT-ON-THE-MAIN, GERMANY

SIEVE

Application filed June 23, 1928, Serial No. 287,806, and in Germany July 2, 1927.

This invention relates to sieves and more particularly to devices of this kind which serve for sifting, separating, sorting or classifying material of any kind. For this purpose heretofore sieves have been used which had been shaken or otherwise properly moved in order to cause the finer particles of the material to fall through the meshes of the sieve. In this case, however, it had been impossible to prevent the meshes of the sieve from clogging-up and special brushes or similar auxiliary devices had to be employed in order to remove the particles of the material which had collected within the meshes of the sieve.

My invention provides a novel sieve, separating, sorting, classifying or sifting device which is of simple and efficient construction and positively avoids the above-mentioned drawbacks inherent to sieves of ordinary construction. More particularly, the device according to my invention is so constructed that it will positively prevent any particles of material from remaining within the meshes of the sieve and that the effect of sifting will be accomplished by the aid of a special auxiliary device which serves for properly distorting the meshes of the sieve. According to my invention the sieve which serves for the reception of the material to be treated is provided with a distorting device having prong-like members that properly engage with the meshes of the sieve, as well as a driving mechanism for imparting to said sieve or said distorting device a proper motion whereby the distorting members proper will periodically engage and distort the meshes of the sieve, in order to cause the finer particles of the material to fall through said meshes. In some cases, especially if sieves are employed having a structure which may easily be damaged, it may be of advantage to construct the distorting device in such a way that it will not immediately engage the meshes of the sieve. For this purpose a modified form of sieve according to my invention may be preferable, this modified sieve comprising distorting prongs which are connected with the meshes so as to project out of the active

surface of the sieve. The distorting device further includes actuating members which serve for operating said prongs so as to impart a periodical distortion to the meshes of the sieve. The distorting device itself may in this case consist of an auxiliary sieve of chain-like structure, a number of upwardly projecting rods or bars being connected with said auxiliary sieve. This distorting device is mechanically actuated by the aid of a driving mechanism in such a manner that said device will make an oscillating or eccentric motion, the said rods or bars coming thus periodically into and out of engagement with the distorting prongs that are rigidly fixed upon the meshes of the sieve. Instead of the aforementioned distorting device also other distorting means may be employed such as, for instance, a metal-sheet having flaps of prong-like conformation which are cut and bent out of said metal-sheet. Furthermore, said distorting means may consist of a circularly moving perforated plate, the prong-like members which are connected with the meshes of the sieve co-operating with the perforations of said plate.

A further modified construction of the sieve according to my invention comprises a distorting mechanism by means of which the material may not only be sifted, separated or sorted but also moved forward upon the active sifting surface of the sieve. This modified construction comprises a fixed sieve equipped with distorting prongs rigidly connected with the meshes of the sieve and further distorting members co-operating with said prongs. In addition to this there is provided a driving mechanism for actuating the distorting device in such a manner that its several members will move periodically past the prong-like extensions on the sieve and in a direction opposite to the desired direction of motion of the material. By this the several meshes of the sieve will always be distorted in the same direction so that the material on the one hand will be sifted, sorted or separated and on the other hand moved forward upon the surface of the sieve. Simultaneously with

this forward motion of the material there will be effected a sifting as well as a sorting of the material according to its specific gravity. This mode of operation will of course essentially accelerate the process of treating the material and dispense with any special devices or contrivances which according to the present practice are necessary for this purpose.

10 A preferred modified construction of the aforementioned kind which may be used for simultaneously sifting and feeding the material to be treated comprises a distorting device consisting of several rollers which are arranged in spaced relation to each other below or above the surface of the sieve and commonly rotated in the same direction, said rollers being provided on their circumference with prongs or similar extensions 15 co-operating with the distorting prongs on the fixed sieve. The driving mechanism may of course also be constructed in different ways, for instance an endless conveying belt carried by a pair of rollers may be used 20 and the actuating members co-operating with the distorting prongs of the distorting device may be fixed on said conveying belt.

25 A still further modified form of the device according to my invention comprises a sieve which is subdivided into a plurality of steps of horizontal or inclined arrangement. According to my invention, however, also a sieve of an elevator-like construction may be used in which the several steps of 30 the sieve are arranged to present a greatly inclined sifting surface, the actuating members for the distorting prongs in this case being intermittently moved in order to impart to the material an almost vertical lifting motion due to the effect of acceleration 35 exerted by the distorting prongs on the sieve. The several steps of the sieve furthermore may be of sieve-like structure so that a thorough sifting will take place simultaneously with the upward motion of 40 the material. The special advantage of this modified construction by means of which the material may be simultaneously sifted and moved forward at a fixed position of 45 50 the sieves consist therein that the mode of operation will be essentially simplified and the cost of construction of the entire plant considerably reduced as compared with heretofore constructed plants of the present 55 kind.

60 A further especially advantageous modified construction may be provided according to my invention by employing a sieve which is made in the form of an endless conveying belt. On the one hand this conveying belt is equipped with a lifting device, such as transverse ledges, and on the other hand with distorting prongs fixed to the meshes of the sieve. The endless belt 65 is furthermore so mounted upon rollers that

there will be produced at least one perpendicular or inclined sifting surface which projects into a container and in addition to this at least one further horizontal sifting surface. On the said perpendicular or inclined sifting surface the material will be lifted out of said container, while on the horizontal sifting surface the material is sifted by action of the distorting prongs which pass the fixed actuating members co-operating therewith.

70 In the accompanying drawings I have shown a few constructions of my improved sieve and the distorting device associated therewith, Fig. 1 being a section through one form of my device, Fig. 2 an enlarged perspective view showing details of the distorting device, Figs. 3 and 4 are partial sections through modified forms of the device, showing forms of the distorting prongs 75 which are rigidly connected with the meshes of the sieve, Fig. 5 is a section through a modified form of sieve serving simultaneously for sifting and conveying of the material, Figs. 6 and 7 show different constructions of distorting devices for stepped sieves, and Fig. 8 shows a further modification of the sieve comprising a rotary conveying and sifting device constructed according to the principles of my invention.

80 Referring more particularly to the drawings, 1 designates a sieve composed of meshes, the material to be sifted, sorted or separated being supplied to said sieve by the aid of a hopper or similar device. The 85 sieve 1 is mounted within a frame 2 and below said sieve there is provided the distorting device in the form of a distorting sieve 4 composed of meshes 5. Upwardly projecting prongs 6 are rigidly connected to the 90 several meshes 5 of the distorting sieve 4, said sieve being suspended intermediate two fixed supporting ledges 11 by means of four springs 10. Motion is imparted to the sieve 95 100 105 110 115 120 125 130 135 140 145 150 155 160 165 170 175 180 185 190 195 200 205 210 215 220 225 230 235 240 245 250 255 260 265 270 275 280 285 290 295 300 It will also be possible without further complicating the devices to impart a rotary motion to the working sieve, for instance by means of an eccentric, in such a manner that the distorting prongs in the uppermost position of the eccentric will engage with the sieve to bring about a distortion of its meshes.

In the construction according to Figs. 3 and 4 the sieves 7 are mounted with a frame 2. These sieves 7, however, are provided with downwardly projecting members 8 which are rigidly connected to the several meshes, said members 8 being shown in Fig. 4 of somewhat greater length than in Fig. 3. The distorting device consists of a metal-plate 9 from which prong-shaped flaps 12 are cut and bent out to project towards above. The metal-plate 9 is connected with the cranks 13. Upon the shaft of the right-hand driving crank there is mounted a sprocket-wheel 23 which engages with the chain 22 and co-operates with the small sprocket-wheel 21 provided on the shaft of the motor 20. The mode of operation in this case is essentially the same as with the aforementioned modification. The members 12 move past the downwardly projecting prongs 8 during each rotation of the crank thus imparting the proper distortion to the meshes of the sieve, the original conformation of the meshes being immediately restored by action of the natural tension of the sieve, whenever the members 12 have passed the meshes.

According to Fig. 4 the prongs 8 engage with the perforations 15 of a perforated plate 14, which is driven by means of a shaft 16 connected to said plate at a point at some distance from its center, said shaft 16 being mounted in bearings 16'. If the plate 14 is rotated, the prongs 8 will be bound to remain upon the surface of the plate, while during passage of a perforation said prongs will enter thereinto. By this also an accelerated motion will be imparted to the sifting prongs therewith producing the desired distortion of the several meshes of the sieve.

As shown in Fig. 5, the working sieve 1 is fixedly mounted within the frame 2 and the meshes of the sieve are again provided with downwardly projecting prongs 8 rigidly connected to said meshes. The material to be sifted is supplied to the sieve by means of a hopper. Below the working sieve 1 there are provided rollers 26 side by side certain distances from each other, said rollers carrying on their circumferences prong-like extensions 27. A sprocket-wheel 28 is mounted exteriorly on each of said rollers, the several sprocket-wheels being connected with each other by means of the chain 24 in such a manner that the direction of rotation of all sprocket-wheels will be the same. The first roller is driven by a special driv-

ing sprocket-wheel, a chain 22 and the sprocket-wheel 21 mounted on the shaft of the motor 20. The several rollers are rotated in the direction indicated by arrows in Fig. 5. The prongs 27 will periodically come in engagement with the prongs of the working sieve and the several meshes of said sieve will thus be periodically distorted. The distortion of the meshes takes place in such a manner that after passage of each of the prongs 27 said meshes will suddenly be pushed backward by action of the natural tension of the structure of the sieve, thus imparting a feeding motion to the material on the sieve as indicated by the arrow shown in Fig. 1 above the sieve. The material will now be fed forward on the surface of the sieve and at the same time sorted, separated or the like, whereupon it will pass into the container 29.

In Fig. 6 the sieve 31 is subdivided into several stepped sieve-surfaces. In this construction there are also provided downwardly projecting prongs 33 at those places 32 of the sieve which form the afore-mentioned stepped surfaces. The prongs 33 will come in engagement with further prongs 35 which are provided on an endless belt 34 carried by the drums 36 and co-operate with said formed prongs. The endless belt 34 is driven by a motor 20, two-sprocket-wheels 21 and 23 and the chain 22 serving for transmitting the motion as shown in the drawing. During motion of the prongs 35 past the prongs 33 an accelerating motion will be imparted to the meshes of the sieve and accordingly the material resting thereon will be moved forward and sifted.

According to Fig. 7 the material is conveyed by means of a supply-hopper 30 to the inclined sieve 31. In this construction the sieve is composed of a plurality of stepped sieve-surfaces 40. The height of the several steps in the present case is somewhat smaller in accordance with the greater inclination of the sieve. The meshes of the sieve are provided with prong-shaped extensions 33 which are actuated by rollers 38 rotating at even speed in the same sense of rotation. On the peripheries of the rollers there are provided prongs 37 which are driven in the manner above described in connection with Fig. 5 by the aid of chains and sprocket-wheels by a motor 20. The material will move in the direction indicated by the arrow in Fig. 7 by being thrown upwardly from one step of the sieve to another and finally discharge into the container 29.

In Fig. 8 I have shown the working sieve 43 constructed as an endless travelling belt. This belt 43 is surrounded by the driving chains and carried over the rollers 42 which deflect the direction of motion of said belt. Each of these deflecting rollers carries on

its outside a sprocket-wheel which is engaged by the driving chain. The endless belt is driven by a special sprocket-wheel 23, a chain 22 and a further small sprocket-wheel mounted on the shaft of the motor 20. Lifting devices in the form of transversely positioned ledges 44 are provided on the sieve or endless belt 43 which ledges are only fastened on the edges of said sieve or belt in order to enhance the flexibility of the latter. Besides, the meshes of the sieve are again equipped with prong-shaped extensions rigidly connected to the several meshes. The distorting device proper forming part of the construction according to Fig. 8 is fixedly mounted within a frame 45 and consists of a plate 47 having a plurality of downwardly projecting prongs 47' which are positioned within the range of action of the members 45. The right-hand end of the sieve or endless belt projects into the main container 48 and the ledges 44 serve for lifting the material out of said container 48. On the upper horizontal main portion of the surface of the sieve the distorting prongs 45 will come in engagement with the members 47 co-operating with said prongs so that the meshes of the sieve will be distorted and the material sifted as above described. Finer particles of the material will be discharged from the device by way of an incline 49 projecting thereinto to a further container (not shown), while the coarser particles which do not fall through the sieve will pass at the rear end of the left-hand upper deflecting roller into a container 30.

This embodiment of my invention may, of course, be constructed with four or more deflecting points in the endless conveyor or sieve whereby a plurality of sieve faces are provided which, for instance, may form a parallelogram. The endless sieve may thus be conducted in any desired course and may be adapted to transport the material along any desired path. The returning section of the sieve may be utilized for sifting the material a second time.

The last described embodiment ensures a very uniform distribution of the material over the sieve and is particularly adapted for moist material which is likely to get stuck in the meshes. Owing to the repeated turning of the material attained in this embodiment, the material is prevented from setting and forming soild blocks which would interfere with an unobstructed passage through the sieve.

The special ledges shown in Fig. 8 for lifting the material from the storage tank may be substituted by other suitable means, for instance the prongs themselves may be formed and arranged to perform this transporting function in addition to their distorting function.

The arrangement with the revolving sieve

band is particularly adapted for drying plants. In this case, means are provided which conduct a gaseous heated drying medium, such as hot air, through the falling material and which, owing to the easy accessibility of the sieve, may be arranged in a very efficient position.

I desire to be understood that my invention is not confined to the exact constructions described herein. My invention, generally speaking, may be employed with all kinds of sieves or similar devices which serve for sifting material, for instance ores, coal-dust, cement and the like, of organic as well as of inorganic nature, it being further immaterial whether the material is subjected to a dry or wet process of treatment.

I claim :

A device for sifting, sorting or separating and conveying material, comprising a working sieve having a stationary and immovable frame and composed of meshes, distorting prongs rigidly connected to said meshes, at spaced points from the surface of said sieve, a plurality of spaced rollers mounted adjacent to said sieve, driving means for commonly imparting uni-directional motion to said rollers, and prong-like extensions on the periphery of said rollers, said prong-like extensions being cooperative with said distorting prongs.

In testimony whereof I affixed my signature.

ERNST HEYMAN.
